UNITED STATES PATENT OFFICE

104,912

DESIGN FOR A SHOE

Benjamin Benjamin, Freeport, N. Y.

Application May 5, 1937, Serial No. 69,181

Term of patent 3½ years

To all whom it may concern:

Be it known that I, Benjamin Benjamin, a citizen of the United States of America, residing in Freeport, Long Island, county of Nassau, and State of New York, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view thereof.

I claim:

The ornamental design for a shoe substantially as shown.
